7 Claims. (Cl. 250—63)

Our invention relates to a method of manufacturing devices for screening-off scattered X-rays as are frequently used when taking X-ray photographs.

5 An object of our invention is to make a screening device of such a construction, that it needs not be moved for sweeping out the shadows of the grid during operation in radiography.

10 A further object of our invention is to facilitate the manufacture of screening devices having extremely thin laminations.

The essential features of our invention will be readily understood by reference to the accompanying drawing in which

15 Fig. 1 is a sectionized view of a portion of a screening device to which our invention is applicable.

Fig. 2 is a plan view of a sheet of a material from which we make the device shown in Fig. 1.

20 Fig. 3 is a sectionized view of a greatly enlarged scale of a portion of the sheet shown in Fig. 2, and

Fig. 4 is a front view of a portion of the said sheet at another scale.

25 Referring to Fig. 1, the device shown thereby consists of strips or laminations 1 of lead, alternating with layers of paper or like fibrous material 2.

We prefer to make the strips with an extremely 30 small width, for example 0.1 mm. or still smaller. By those means we obtain the advantage, that in operation the screening device will not cast inconvenient shadows on the photographic plate, even when kept stationary during the exposure. 35 Consequently the screening device will not deleteriously affect the quality of the X-ray image.

On the other hand, we reduce as much as possible the width of the strips in order to prevent that the useful beam of primary X-rays will be 40 partly absorbed by the strips, due to the inclination of the primary X-rays, which increases with the distance from the centre. A width of a few millimeters or preferably 1.5 mm. is a suitable dimension for devices of this kind. The mutual distance of the strips may then be about 0.2 mm.

In manufacturing the grid structure shown in Fig. 1, lead strips 1 and intermediate layers 2 transparent to X-rays may be joined together by means of an agglutinant. However we have 50 found, that it is difficult to manufacture screens having a sufficiently fine grid, for example screens having two laminations per mm., due to the fact that the lead material for such a screen can only be handled with great difficulty because of its 55 thinness. Strips of lead having a thickness of

say 0.1 mm. or less are very supple and it is not easy to bring them at the right place while maintaining their smooth surface. Sheet material from which the strips are cut is also very difficult to be handled and will readily be torn as it has very little mechanical resistance.

According to our invention we eliminate these drawbacks by applying a layer of paper or similar material to the lead sheet material before cutting out the strips. For example a sheet of lead 10 of the form represented in Fig. 2 and measuring 50 cm. long by 40 cm. wide is lined with a layer of paper and then cut into strips.

The coating of paper may be applied either to one side of the sheet or to both sides. It is attached to the lead surface by means of an agglutinant. When covering the lead sheet at either side, the layers of paper may be of equal thickness or, as shown in Fig. 3, they may have a different thickness. In the example shown in Fig. 20 3 a sheet 3 of lead having a thickness of about 0.1 mm. has applied to one of its sides a sheet of paper 4 having a thickness of 0.07 mm. and to the other side a sheet of paper 5 having a thickness of 0.14 mm. The latter may consist of a double 25 coating of paper consisting of two layers, each of the same thickness as layer 4.

The sheet thus treated may be cut into strips along the lines 6, shown in Figs. 3 and 4, the width 20 being 1.5 mm. e. g. and then these strips are 30 glued together to form a grid.

The coatings 4 and 5 have together the thickness corresponding to the desired distance between the absorbing laminations of the completed grid. However it is also possible to provide 35 additional insert strips of a material pervious to X-rays and so obtain the desired thickness of the interspaces.

By applying coatings of paper or similar material to the lead sheets, the latter are stiffened, 40 even if only one side thereof is coated, to such an extent, that in the manufacture of the laminations it can be handled without any difficulty. The rigidity may still be increased by pasting together one or more sheets, provided with coatings on both sides as shown in Fig. 3 or with a coating of the same total thickness on one side. From the multiple layer obtained thereby strips or rods may be cut having the desired width and these strips or rods may be glued together to form 45 a continuous plate of the form shown in Fig. 1.

The attachment of the layers to the lead sheet and the mutual attachment of the strips to build up the grid screen, is preferably effected by means of a non-hygroscopic agglutinant, which has a 55

consistency such that it is absorbed by the material of the layer, owing to which this material becomes at the same time less sensitive to moisture.

5 5. What we claim is:

1. A method of making a grid for screening-off scattered X-rays, comprising the steps of coating a thin sheet of lead with a layer of fibrous material to produce a composite sheet which can be accurately cut, cutting the composite sheet into narrow strips, and assembling the strips side by side to form the grid.

10 2. A method of making a grid for screening-off scattered X-rays, comprising the steps of agglutinating a layer of paper to each side of a thin sheet of lead to produce a composite sheet which can be accurately cut, cutting the composite sheet into narrow strips, and uniting the strips with their flat sides together.

15 3. A method of making an X-ray grid having lead laminations and intermediate laminations of X-ray transparent material, comprising the steps of agglutinating to a thin sheet of lead a layer of fibrous material having the thickness of the intermediate laminations to thereby produce a composite sheet which can be accurately cut, cutting the composite sheet into narrow strips, and assembling the strips in the same relative positions to form the grid.

20 30. 4. A method of making an X-ray grid having

lead laminations and intermediate laminations of X-ray transparent material, comprising the steps of applying to both sides of a thin sheet of lead layers of fibrous material whose total thickness is equal to the thickness of one of the intermediate laminations to thereby produce a composite sheet which can be accurately cut, cutting the composite sheet into narrow strips, and assembling said strips in the same relative positions to form the grid. 5

10 5. An X-ray grid comprising a plurality of composite strips arranged side by side, each of said strips comprising a narrow strip of lead provided with a surface coating of fibrous material.

15 6. An X-ray grid comprising a plurality of composite strips each having a strip portion of lead provided on one side with a coating of fibrous material, and strips of X-ray transparent material between said composite strips. 15

20 7. An X-ray grid comprising a plurality of composite strips each having a strip portion of lead provided on one side with a coating of paper having a thickness less than that of one of the lead strip portions, and a strip of X-ray transparent material between adjacent composite strips and having a thickness greater than that 25 of one of the lead strip portions.
